UNITED STATES PATENT OFFICE.

CHARLES LAURENCE BURDICK, OF LONDON, ENGLAND, ASSIGNOR OF ONE-HALF TO
JOHN BENJAMIN PARNHAM, OF CHINGFORD, ESSEX, ENGLAND.

COIN-ACTUATED MACHINE.

1,323,214.

Specification of Letters Patent. Patented Nov. 25, 1919.

Application filed February 10, 1919. Serial No. 276,084.

To all whom it may concern:

Be it known that I, CHARLES LAURENCE BURDICK, a citizen of the United States of America, residing at 4 Eastern road, Wood

5 Green, London, England, have invented new and useful Improvements in Coin-Actuated Machines, of which the following is a specification.

This invention relates to coin actuated 10 machines of the kind wherein provision is made for taking a record of the number of coins introduced into the machine and furnishing a printed record so as to obviate errors or peculation on the part of employees, as described in the specification 15 of former British Letters Patent No. 21279 A. D. 1913, the object of the present invention being to improve the construction of this machine and to render it more efficient in operation.

According to the present invention I modify the construction described in the said former specification in the following manner, that is to say, I combine with the bolt 25 which secures the coin receptacle a lock which secures the bolt and which is so constructed that the key of such lock cannot be removed after the bolt is withdrawn until the bolt has been returned to secure 30 the said coin receptacle. Also I advantageously provide for introducing separate slips of paper into the machine as foreshadowed in the said earlier specification, but I now arrange that the insertion of these 35 slips will practically form a part of the operation of unlocking the machine to enable the withdrawal of the coin receptacle, that is to say, I provide in connection with the lock a stop which prevents the complete 40 insertion of the key into the lock until the said stop has been removed by the introduction of the paper. I furthermore provide that the longitudinal movement of this bolt after it has been unlocked shall effect 45 the operation of the printing mechanism, and that the return of such bolt to its locking position shall set the numbering disks back to zero.

In the accompanying drawings—
50 Figure 1 is a sectional plan of the improved apparatus.

Fig. 2 is a sectional end elevation of the same, and

Fig. 3 is a sectional front view.

Fig. 4 is a section on the line 4—4, Fig. 3, 55 with the key inserted into the lock.

Fig. 5 is approximately a section on the line 5—5, Fig. 4.

Fig. 6 is a view similar to Fig. 4 but showing the position of the key when turned 60 to unlock the bolt.

Fig. 7 is a view of the key detached.

Fig. 8 is an elevation of one of the wheels of the numbering mechanism.

a indicates the casing of the well-known 65 slot mechanism used in connection with gas meters and beneath which is a receptacle or drawer *b* for the coins, the compartment *a* having arranged within it a rotating member or wheel *c* which receives the coins 70 placed in the slot and when operated by the usual knob communicates motion to the shaft *c*¹ sets the mechanism of the meter (not shown) in a position for the delivery of the gas in a well known manner. 75

d is a lever which is depressed or operated by a coin as the wheel *c* is rotated, and the movements of which lever are communicated by ratchet and pawl mechanism *d*¹ to the numbering mechanism *e* which is similar to 80 that described in the said former specification but arranged with the axis of its shafts *d*² in the same direction as the axis of the shaft *c*¹ instead of at right angles thereto. This numbering mechanism is arranged in the 85 casing *f*, and on a frame or bracket *f*¹ arranged within the said casing, is placed a bolt *f*² which normally projects into a slot in the drawer *b*. This bolt is adapted to be moved longitudinally to engage it with 90 or disengage it from the said drawer by means of a knob *g* having on it a pinion *g*¹ which engages with rack teeth *g*² on the said bolt. The improper movement of the bolt *f*² is prevented by a lock which 95 comprises a barrel or stud *h* rotatably mounted in a hole in said bolt, one section of this barrel being flattened as at *h*¹, Figs. 3 and 4, so that it can, when turned into coincidence with a slot *h*² formed in the 100 frame *f*¹, slide longitudinally, but when turned at right angles thereto, as shown in Fig. 3, will not enter the said slot.

A key-way or slot *i* is cut through the barrel *h* which permits of the insertion of 105 a flattened key so that by turning the barrel through an angle of 90° the bolt *f*² can be moved longitudinally with relation to the

frame f^1 , and that when the barrel is turned so that the flattened portion is in the position shown in Fig. 3, the said bolt will be again locked with relation to the casing.

5 To secure the retention of the barrel h in the locked position I provide on its inner face an extension piece i^1 having its extremity turned at right angles in alignment with the bolt f^2 , as indicated at i^2 Fig. 4, 10 thus forming a stop to limit the distance that the key shall be inserted into the said slot. This flanged end i^2 is, however, cut away or notched as indicated at i^3 to permit the reception of spring actuated fingers or 15 strips j which engage the said notches and prevent the barrel from being turned unless pressed back by the key k , Fig. 7, as indicated in Fig. 4, the said key being cut with projections k^1, k^1 which enter the notches i^3 to press back the said fingers j .

As with the locking arrangement an operator might unlock and open the machine without inserting the slips of paper to be printed I guard against this by mounting 25 within the casing adjacent to the barrel h , a well balanced pivotal piece l so arranged with relation to the key slot i that it will lie in front of one of the said fingers j , as shown clearly in Fig. 2, and when in this 30 position prevent such spring finger from being pushed back by the key k so that the latter cannot be properly introduced into the barrel until the said pivotal piece l is moved out of the path of the said spring 35 finger.

The movement of the pivotal piece l is effected by means of the paper slips, to allow of which the said pivotal piece has an arm l^1 which projects into the path of the 40 slips the latter being introduced into the casing through a guide tube m . To secure greater strength and rigidity in the paper slips to operate the pivotal piece l , I propose to bend down the edges thereof and I there- 45 fore provide the groove or slot m with right angled extensions m^1, m^1 into which the said bent down edges of the paper sheets will enter.

The introduction of the paper slips as be- 50 fore described having allowed the spring fingers j, j to be pushed backward out of the notches i^3 the barrel h can be turned to bring the flattened portion h^1 into alignment with the slot h^2 and thereby allow the bolt 55 f^2 to be withdrawn from engagement with the coin drawer so that the coins can be removed. This withdrawal of the bolt serves to effect the printing of the number presented uppermost by the numbering 60 disks by pulling down the frame n which carries a platen n^1 to press the paper slips on to the said printing surface.

To effect the downward movement of the frame n^1 a lever o is pivoted within the cas- 65 ing at o^1 , one end of which lever engages

with the said frame as at o^2 , while the other end enters a slot p in a cam-plate p^1 fixed to the bolt f^2 .

With this arrangement the withdrawing movement of the bolt f^2 indicated by the 70 arrow, Fig. 3, causes the end of the lever o in the slot p to move upward under the action of a cam surface p^2 and then move again downward to return the said frame n to its normal position. The cam surface p^2 75 is formed upon a pivoted bar p^3 so that when the bolt f^2 is moved in the opposite direction to that indicated by the arrow, Fig. 3, the roller on the end of the lever o will pass under or out of contact with the 80 cam surface p^2 so that no movement will be imparted to the platen.

In order to provide that the key k shall not be removed from the lock until the bolt 85 f^2 is replaced and the said key turned to 90 lock the said bolt, I provide a spring actuated finger q which forms one arm of a two armed spring secured to the lock barrel by a pin q^1 . When the barrel is in the locking position, as indicated in Figs. 4 and 5, 95 this spring arm q bears upon a stop or abutment q^2 so that the key can be inserted between the two arms of the spring, the lower arm thereof bearing against the underside of the key and being forced thereby out of line with a stop q^3 which normally obstructs the movement of the said arm and consequently of the barrel if an attempt be made to turn the barrel with an instrument 100 other than the proper key.

When the key k is inserted and the rotation of the barrel takes place, as indicated in Fig. 6, the arm q springs into a notch q^4 and remains in that position until after the 105 bolt has been operated as hereinbefore described and is returned to its normal position in which the spring arm q rests upon the stop q^3 out of engagement with the notch q^4 of the said key.

q^4 indicates an additional notch in the 110 key k which enables it to clear the bracket or upright r carrying the stop q^2 and which bracket or upright is fixed to the casing.

If for any reason the arm q did not enter the notch q^4 in the key k a stop q^5 on the 115 bracket r and located above the said arm would prevent it and consequently the barrel h from being rotated by the key.

In order that the operation of the bolt for locking the drawer shall return the number 120 disks e to zero on the shaft d^2 I arrange the latter so that it can rotate freely within the said disks, and on the end of the said shaft I fix a bevel pinion s with which another 125 bevel pinion s^1 engages, this latter pinion being fixed to a shaft t having loosely mounted upon it a pinion t^1 which engages with the rack teeth g^2 on the bolt f^2 . This pinion t^1 has formed integrally with it a sleeve 130 carrying a disk u having in it a notch with

which a pawl u^1 on a disk u^2 fixed to the shaft t is designed to engage for rotating the said shaft and consequently the shaft d^2 through the medium of the wheels s , s^1 .

5 With this arrangement when the bolt f^2 is drawn back clear of the coin drawer b no movement will be imparted to the shaft d^2 owing to the notched disk u slipping under the pawl u^1 , when, however, the bolt is 10 moved in the reverse position, the movement of the shaft d^2 will take place as before described.

The shaft d^2 has formed in it a longitudinal ratchet groove v (Fig. 8) with which 15 a pawl v^1 on the several numbering disks e can engage in such a manner that when the said shaft is rotated all the numbering disks will be moved to the requisite distance as described in the specification of my said 20 former patent.

The usual spring actuated detent w in connection with each disk e secures that the alignment of the several figures of the disks shall be perfect.

25 The operation of the machine is as follows:—When a coin is inserted into the machine and the coin wheel c has been turned by the operating knob to automatically deliver the gas or other commodity, the numbering disks are advanced one unit.

When the coins are to be collected the sheet or slip of paper (with copy carbon if desired) is inserted into the slot m with its edges turned down, as indicated by the dotted lines in Fig. 2, which sheet of paper by contact with the arm b^1 moves the pivotal piece l as before described, the key k can now be pushed into the slot i and the barrel h of the lock rotated to a position to free the 35 bolt f^2 . The collector now withdraws the bolt from the coin receptacle b and at the same time brings the platen n down on the paper to print and obtain a record of the number of coins together with the number 40 of the particular machine.

The bolt f^2 having been withdrawn the drawer b can be opened. The replacing of the said bolt to again lock the drawer automatically sets the disks e at zero, and when 45 the bolt f^2 is in its full locking position the key can be removed from the lock.

Claims:

1. In coin actuated mechanism of the kind hereinbefore referred to the employment in 50 connection with a bolt which secures the money receptacle, of a lock which is operated to release the bolt before the latter can be moved, a key for the lock and mechanism

designed to retain the key in the lock until the bolt has been replaced, substantially as 60 described.

2. In coin actuated mechanism of the kind hereinbefore referred to the employment in connection with a sliding bolt which locks the money drawer, of a lock which is operated to release the bolt before the latter can be moved, such lock having combined with it a stop which prevents the complete insertion of the key into the lock until the said stop has been removed by the introduction 70 of the paper upon which the record is to be obtained, substantially as described.

3. In coin actuated mechanism comprising a bolt combined with a lock as claimed in claim 1, the arrangement whereby the 75 printing of the record is effected by longitudinal movement of the bolt, substantially as described.

4. In coin actuated mechanism comprising a bolt combined with a lock as claimed 80 in claim 1, and adapted to effect the printing during the movements of the bolt as claimed in claim 3, the combination with the bolt of a divided cam piece that serves to operate the printing platen during the 85 movement in one direction, and to pass the lever operating such mechanism in the reverse direction, substantially as described.

5. In coin actuated mechanism comprising a bolt combined with a lock as claimed 90 in claim 1, the combination with the said lock of means for preventing the operation of the lock to release the bolt until the slip upon which the record is to be taken has 95 been inserted to push back the stop above referred to which allows the operation of the lock, substantially as described.

6. In coin actuated mechanism comprising a bolt combined with a lock as claimed 100 in claim 1, and provided with means whereby the lock can only be operated after the insertion of the record paper as claimed in claim 5, the construction of the slot into which the said record paper is inserted, with angular extensions for receiving the 105 bent down edges of the paper, substantially as described.

7. In coin actuated mechanism comprising a bolt combined with a lock as claimed 110 in claim 1, the combination with the said lock of a spring device which when the barrel is turned engages with the key and prevents the withdrawal of the key until such time as the lock is restored to its locking position, substantially as described.

CHARLES LAURENCE BURDICK
